UNITED STATES PATENT OFFICE.

JOHN JACK, OF GLASGOW, SCOTLAND.

MACHINE FOR DRYING AND TARRING ROAD METAL.

1,408,512.

Specification of Letters Patent. Patented Mar. 7, 1922.

Application filed June 18, 1920. Serial No. 390,009.

(GRANTED UNDER THE PROVISIONS OF THE ACT OF MARCH 3, 1921, 41 STAT. L., 1313.)

To all whom it may concern:

Be it known that I, JOHN JACK, of Lily-
vale, Copland Road, Govan, in the county
of the city of Glasgow, Scotland, quarry
5 master, have invented certain new and use-
ful Improvements in and Connected with
Machines for Drying and Tarring Road
Metal, (for which I have filed an applica-
tion in Great Britain January 24, 1919,
10 Serial No. 1824, Patent No. 133,571), of
which the following is a specification.

My invention relates to machines for drying
and tarring road metal, and has for its
object to simplify their construction by de-
15 creasing the number of parts and rendering
them more efficient in practice. I am aware
that it has been previously proposed to use
a cylinder rotating over a furnace comprising
several sections for receiving, drying,
20 heating, tarring and delivering the road
metal with suitable perforations and with
internal vanes for feeding the road metal
through the cylinder, and also a heating
drum disposed within a drying drum and
25 surrounded by a mixing drum, the feeding
and delivery drums tapering in opposite
directions.

According to my invention, I form the re-
volving casing of a conically-shaped receiv-
30 ing chamber, a cylindrical-shaped tarring
chamber, and a conically-shaped delivery
chamber, the said chambers being in line
with each other, and the taper in the first
and last mentioned chambers being in op-
35 posite directions, a zig-zag baffle being pro-
vided in the receiving chamber. Buckets or
lifters are also provided in the tarring cham-
ber and a screw conveyer in the delivery
chamber for conveying and delivering the
40 material after final treatment.

In order that my invention may be prop-
erly understood and readily carried into
effect, I have hereunto appended an ex-
planatory sheet of drawings representing
45 the machine embodying my invention in
longitudinal section.

The revolving casing is represented by A,
B and C, A indicating the receiving conical
chamber, B the central cylindrical chamber
50 and C the delivery chamber which latter
may be connected to the central portion by
bolts. Immediately over the receiving por-
tion is the tar tank or reservoir D and be-
low it the furnace E while the flues F pass
55 around the revolving casing and the pro-

ducts of combustion are carried to the vent
or uptake G. A pipe H leading from the
tank or reservoir D conveys the tar into
the interior of the hollow revolving shaft I.
The revolving shaft I is perforated at that 60
portion thereof within the said central
cylindrical casing B and the tar percolates
through holes I¹.

Within the interior of the revolving
chamber A of the revolving casing, is 65
mounted the baffle arrangement J composed
of a number of plates disposed in zig-zag
formation and connected to the inner wall
of said casing. The said baffle arrangement
may conveniently be in the form of a helix 70
carrying the stones along during the rota-
tion of the revolving casing and dropping
them into the central chamber B where they
receive a coating of tar which percolates
and drips through the holes I¹ formed 75
around the wall of the hollow revolving
shaft preparatory to being lifted up by the
buckets or lifters K which are raised with
the revolving of the casing and deposited
into the delivery chamber C of said revolv- 80
ing casing on reaching which the screw con-
veyer L in its rotation moves the material
forward and delivers it into the receptacle
M, shown in dotted lines. The delivery part
of the casing C is of conical formation or 85
tapered so that should any of the tar get
into it during the conveyance of the ma-
terial the tar flows down the incline and
finds its way back again into the tar well
formed in the central cylindrical chamber 90
B. Any superfluity of tar on the metal dur-
ing the rotation of the revolving casing is
prevented from getting into the delivery
chamber by the baffle N the tar striking
against the baffle and again dropping into 95
the well. The improvements with a slight
variation may be adapted to a portable ma-
chine carried upon wheels.

Claims—

1. A machine for drying and tarring road 100
metal, comprising a revolvably mounted cas-
ing having a frusto-conical receiving
chamber at one end, an intermediate cylin-
drical tarring chamber, and a frusto-conical
delivery chamber at the opposite end, said 105
chambers being in line with one another,
said intermediate chamber being of greater
diameter than the greatest diameter of the
receiving and delivering chambers and
forming a tar well, and said receiving and 110

delivering chambers tapering in opposite directions and arranged with their smaller ends outermost, so that the flow of tar is facilitated through the receiving chamber 5 to the intermediate chamber and is prevented from the intermediate chamber through the delivery chamber, zig-zag baffle plates arranged in the receiving chamber, buckets or lifters in the tarring chamber, 10 and a screw conveyer in the delivery chamber to convey and deliver the material after final treatment.

2. A machine for drying and tarring road metal, comprising a revolvably mounted casting having a frusto-conical receiving chamber at one end, an intermediate cylindrical tarring chamber, and a frusto-conical delivery chamber at the opposite end, said chambers being in line with one another, 15 said intermediate chamber being of greater diameter than the greatest diameter of the receiving and delivering chambers and form-

ing a tar well, and said receiving and delivering chambers tapering in opposite directions, and arranged with their smaller ends outermost, so that the flow of tar is facilitated through the receiving chamber to the intermediate chamber and is prevented from the intermediate chamber through the delivery chamber, zig-zag baffle plates arranged in the receiving chamber, buckets or lifters in the tarring chamber, a screw conveyer in 30 the delivery chamber to convey and deliver the material after final treatment, and a baffle in the larger end of the delivery chamber to prevent tar from getting into such chamber.

35 In testimony whereof I affix my signature in presence of two witnesses.

JOHN JACK.

Witnesses:

JOHN LIDDLE,
JOHN TRAIN LIDDLE.
